UNITED STATES PATENT OFFICE.

FRANK H. KRIENITZ, OF McFARLAND, KANSAS.

INTERNAL-COMBUSTION ENGINE.

1,281,981.

Specification of Letters Patent. Patented Oct. 15, 1918.

Application filed August 10, 1917. Serial No. 185,553.

To all whom it may concern:

Be it known that I, FRANK H. KRIENITZ, a citizen of the United States, residing at McFarland, in the county of Wabaunsee and

5 State of Kansas, have invented new and useful Improvements in Internal-Combustion Engines, of which the following is a specification.

This invention relates to internal combustion engines, the broad object in view being to provide a compact and powerful light-weight engine of simple, practical and strong construction embodying multiple cylinders and pistons, all of the pistons reciprocating as a unit, the cylinders being stationary, and the pistons being all connected to a single wrist pin which is in turn connected by side connecting rods to a crank shaft located at one end of the block of 20 cylinders.

One of the chief objects of the present invention is to provide novel valve actuating mechanism for controlling the inlet and exhaust of the cylinders, the valve mechanism 25 being also compact, simple, reliable and readily accessible.

With the above and other objects in view, the invention consists in the novel construction, combination and arrangement of parts, 30 herein described, illustrated and claimed.

In the accompanying drawings:

Figure 1 is a horizontal section through a multiple cylinder engine embodying the present invention.

35 Fig. 2 is a vertical longitudinal section through the same.

Fig. 3 is an end elevation thereof.

Fig. 4 is an inside face view of one of the combined cylinder heads and valve chamber 40 blocks.

Fig. 5 is a vertical cross section on the line 5—5 of Fig. 2.

In the preferred embodiment of this invention I provide a plurality of cylinders 1 45 preferably cast in block and arranged end to end in horizontally opposed relation. As shown in Fig. 1, there are four cylinders in the engine illustrated, the cylinder being arranged in horizontally opposed pairs and 50 containing reciprocating pistons 2. All of the piston rods 3 are connected to a common wrist pin 4. The wrist pin 4 projects on opposite sides of the block of cylinders, said block being formed in the opposite walls 55 thereof with longitudinal slots 5 through which the wrist pin 4 works. Connecting

rods 6 are attached at one end to the opposite extremities of the wrist pin 4 and are attached at their opposite extremities to a pair of crank arms 7 arranged at opposite 60 sides of the block of cylinders and forming parts of the crank shaft 8 which is journaled in bearings 9 on the adjacent cylinder head.

Multiple cylinder heads or cylinder head blocks 10 are arranged at each end of the cylinder block and are secured in place by bolts 11 so that they may be readily detached for cleaning purposes. Each cylinder head 10 is of proper shape and size to cover two of the cylinders 1 and each of said cylinder heads 10 also constitutes a valve chamber, being formed with the chamber 12 in which is mounted a reciprocatory piston valve 13. Each piston 13 controls an intake port 14 and an exhaust port 15. Each piston 13 is 70 operated by means of a connecting rod 16 which is attached to the piston by a piston pin 17. The opposite extremity of the connecting rod 16 is connected by a pivot 18 to one arm of a bell crank lever 19 journaled in a hanger 20 extending downwardly from and secured to the cylinder block. Pivotally connected to the other arm of the bell crank lever 19 is a pull and push rod 21 having at its inner end a projection 22 which 75 works in a cam slot 23 in a cam 24. A cam 24 is employed for operating each piston valve 13, the groove in the cam being designed to cause the reciprocatory piston valve to cover and uncover the intake and 80 exhaust ports 14 and 15 at the proper moments.

The cam 24 is fast upon a rotary cam shaft 25 journaled in shaft hangers 26 secured to and extending downwardly from the cylinder block. The shaft 25 extends beyond one end of the cylinder block where it is supported by another hanger 27 secured to and extending downwardly from the adjacent cylinder head 10. On the extremity of the shaft 25 is a bevel gear 28 which meshes with and is driven by another bevel gear 29 on a countershaft 30. The countershaft has another gear 31 which meshes with a gear 32 on the crank shaft 100 105 8. The cam shaft is thus driven by a suitable gear from and by the crank shaft, the cam shaft rotating at one-half the speed of the crank shaft in accordance with four cycle practice.

110 From the foregoing description taken in connection with the accompanying drawings

it will be seen that I have produced a simple, compact, light-weight and reliable multiple cylinder internal combustion engine in which all of the pistons move as a unit and 5 in which the cylinder heads constitute also valve chambers which are bored to admit of the reciprocatory movements of the piston valves in planes perpendicular to the axis of movement of the pistons. This admits of the arrangement of the cam shaft as shown and described, the cam shaft extending under the block of cylinders and parallel to the path of movement of the pistons. The simple actuating connections be- 10 tween the cams on the cam shaft and the piston valves, insures an accurate timing of said valves thereby obtaining the highest power efficiency from the engine. Furthermore the valves may be easily removed and 15 ground or cleaned and all of the valve actuating connections are accessible. The engine may be either air cooled or water cooled as may be preferred and any suitable lubricating system and ignition system may be 20 employed, it being understood that the explosions take place between the piston heads and the cylinder heads.

I claim:—

In an internal combustion engine, a plurality of cylinders arranged end to end and 25

formed in block, reciprocatory pistons working therein, a common wrist pin to which all of said pistons are connected, a crank shaft journaled in bearings at one end of the cylinder block and supported by one of the cylinder heads, connecting rods between said crank shaft and the opposite extremities of said common wrist pin, combined cylinder heads and valve chambers detachably fastened to opposite ends of the cylinder block, each of said cylinder heads embodying a cylindrical bore forming a valve chamber extending perpendicularly to the path of movement of the pistons, piston valves mounted to reciprocate in said valve chambers, a rotary cam shaft parallel to the path of movement of the pistons and journaled in bearings supported by the block of cylinders, said cam shaft being geared to and driven by the crank shaft, valve operating connections between said cam shaft and said piston valves, said operating connections embodying a cam actuated push and pull rod, a bell crank lever controlled by the last named rod, and a connecting rod controlled by said bell crank lever and attached to the respective piston valve.

In testimony whereof I affix my signature.

FRANK H. KRIENITZ.
